UNITED STATES PATENT OFFICE.

BONAPART ALLEN, OF BUFORD, GEORGIA.

DESIGN FOR A HORSE-COLLAR.

SPECIFICATION forming part of Design No. 26,362, dated December 1, 1896.

Application filed September 23, 1896. Serial No. 606,788. Term of patent 7 years.

To all whom it may concern:

Be it known that I, BONAPART ALLEN, a citizen of the United States, residing at Buford, in the county of Gwinnett and State of Georgia, have invented and produced a new and original Design for a Horse-Collar; and I do hereby declare the following to be a full, clear, and exact description of the invention, such as will enable others skilled in the art 10 to which it appertains to make and use the same.

My design consists, essentially, of a horse-collar having a continuous integral top portion in the form of a segment of a circle of a short radius and being bifurcated at its lower 15 end or throat, approximately along the median line thereof, the ends of said bifurcations facing each other, and the said throat portion of each bifurcation widening rearwardly and 20 downwardly toward the end thereof, and having a thin curved flap on the inner side of said throat portion resting upon and overlapping the adjacent ends of both of said bifurcations, as shown in the drawings.

In the accompanying drawings, which illustrate a horse-collar embodying my design, Figure 1 is a front view of the collar as fastened, and Fig. 2 is a view looking at the bottom thereof as unfastened.

A designates the integral continuous segmental portion at the top of the collar.

A' A' designate the two bifurcations of the throat of the collar.

A² A² designate the widening ends of said bifurcations, and C represents the thin flap 35 overlapping the ends of said bifurcations on the inner side of the throat of the collar.

What I claim is—

The design for a horse-collar substantially as herein shown and described. 40

In testimony whereof I affix my signature in presence of two witnesses.

BONAPART ALLEN.
